CALKING WELT

Lloyd F. Plummer, Brockton, Mass., assignor to
The Brockton National Bank, as trustee

Application April 17, 1931, Serial No. 530,799
Renewed January 15, 1937

14 Claims. (Cl. 36—78)

The present invention relates to weltting which is used in the manufacture of welt shoes, and more particularly, but not exclusively, to the art of making a calking welt which is secured, with the welt, to the upper and insole of a welt shoe by the inseam stitches, and which is used to calk the shoe crease formed between the upper and the welt to exclude dirt and moisture and to impart to the shoe a heavy and storm-proof appearance.

It has been proposed heretofore to use a calking welt of the type referred to in which the face thereof which is exposed to view in the finished shoe is a grain face presenting inherently an attractive appearance. This grain face has a free end face that may engage the exposed face of the welt and a flesh face that is secured by cement to a vertical flesh face on the body portion of the calking welt. As constructed heretofore there was a tendency for the free end face of the grain face to lift away from the welt or the upper, as the case may be, and expose to view a flesh face of the body portion of the calking welt and thus destroy its attractive appearance.

The principal object of the invention is to produce a calking welt composed of a single strip of material which, when inserted into the crease formed between the upper and the welt of a welt shoe and secured, with the welt, to the upper and insole by the inseam stitches, will present to view a grain face which is locked in position on the body portion of the strip by the cooperative action of the original free end face of the grain face and the shoe part engaged by said end face.

To the accomplishment of this object, and of others which will appear hereinafter, the various features of the present invention reside in certain constructions, arrangements of parts, step products, and methods of manufacture hereinbefore described and then set forth broadly and in detail in the appended claims which possess advantages readily apparent to those skilled in the art.

The various features of the present invention will be understood readily by those skilled in the art from an inspection of the accompanying drawing, illustrating the best form of the calking welt at present devised, the preferred method of making it and one mode of incorporating it into a welt shoe, in which,

Figure 1 is a view in sectional elevation of a welt shoe showing the improved calking welt located in the crease formed between the welt and the upper;

Fig. 2 is a detail view in perspective of a

standard strip of Goodyear shoe welting illustrating the step of removing a triangular strip from the grain face thereof along the inner edge face to form a flange thinner than the standard strip;

Fig. 3 is a detail view in perspective of the same strip of material shown in Fig. 2 illustrating the step of removing from the flesh face thereof a triangular strip leaving the outer edge face intact;

Fig. 4 is a detail view in perspective of a step product in the manufacture of calking welts, the intact outer edge face and the grain face being molded to close up the gap formed in the flesh face by the removal therefrom of the triangular strip shown in Fig. 3 and to convex the grain face, and

Fig. 5 is a detail view in perspective of the improved calking welt which is a product of the final step in the method, the two flesh faces being concaved.

The improved method of making calking welts starts with a standard, rectangular, endless strip of Goodyear Welt Shoe welting 6 (Fig. 2) of a desirable width. The strip 6 is provided with a grain face 7, a flesh face 8, an inner edge face 9, and an outer edge face 10. The strip 6 is formed, as usual, into a continuous strip by scarfing together a number of separate pieces. The scarf joint presents to view, on both the grain and flesh faces, a transverse line 11, and, on the edge faces, a diagonal line 12.

The first step in the improved method of making calking welts consists in removing bodily from the strip 6, either simultaneously or consecutively, two triangular strips 13 (Fig. 2) and 14 (Fig. 3). The triangular strip 13 is removed from the grain face 7 adjacent the inner edge face 9 to leave a rabbet and form a flange thinner than the strip 6 having a tapered flesh face 15 which, however, does not taper to a feathered edge. As this strip 13 is provided with a grain face 7 it has utility in the manufacture of other types of welt and is not waste.

The strip 14 is removed from the flesh face 8 adjacent the outer edge face 10 which is left intact. Removal of the strip 14 from the flesh face 8 forms a groove or rabbet, having two convergent faces 16 and 17, in the body portion of the strip 6. The face 16 meets the flesh face 8. The face 17 meets the intact outer edge face 10 forming therewith a feather edge 18. The width of the gap left in the flesh face 8 by the removal of the strip 14 is substantially com-

mensurate with the thickness of the intact edge face 10.

After the triangular strip 14 is removed from the flesh face 8 cement may be applied to the 5 internal faces 16 and 17. The strip 16 is passed through rolls which are shaped to turn the intact outer face 10 and the grain face 7 about the meeting edge of the faces 16 and 17 to bring them into face to face contact and to convex the 10 grain face, as shown in Fig. 4. The gap 7 formed by the removal of the strip 14 from the flesh face 8 is now closed up and the intact outer edge face 10 is brought into substantially the same plane as the flesh face 8. At least a portion of the intact outer face 10 is brought into a position directly underlying the internal faces 16 and 17.

The step product illustrated in Fig. 4 is tempered in a liquid, preferably water, and then is passed through another set of rolls shaped to 20 impart the final form to the calking welt. These rolls impart a concave curvature to the flesh faces 8 and 15 in order that they may conform to the welt and the upper, respectively, of a Goodyear Welt Shoe.

25 The calking welt 19 (Fig. 5) is secured to the upper 20 and the insole 21 of a Goodyear Welt Shoe by the same inseam stitches 22 which secure the standard welt 23 to the upper and insole. In fact the calking welt 19 and the standard welt 23 are secured to the upper 20 and the insole 22 in the usual inseam sewing operation.

As shown in Fig. 1 the concaved flesh faces 8 and 15 of the calking welt 19 conform to the curvature of the welt 23 and the upper 20, respectively, adjacent the inseam. The convexed grain face 7 extends from the upper 20 to the welt 23 and completely fills the crease formed between the upper and the welt and thus excludes dirt and moisture and imparts to the shoe a heavy and storm-proof appearance. As the only 40 portion of the calking welt 19 which is exposed to view is a grain face, the calking welt is inherently attractive in appearance, is capable of receiving a high finish, and may be ornamented in a pleasing manner. The scarf line 11 is exposed to view in the finished shoe as a short vertical line, easy to finish and attractive in appearance.

The original intact outer face 10 of the strip is now hidden as it engages the welt 23 with at 50 least a portion of said face underlying the internal faces 16 and 17. The body portion of the calking welt 19 thus impacts the original intact edge face 10 against the welt 23 so that it is impossible for the internal faces 16 and 17 to 55 separate in use whether or not they are cemented together. With this construction the convexed grain face 7 is fastened or locked securely in its proper position by the engagement of the intact edge face 10 with a part of the shoe which, for the purposes of the present disclosure is the welt 23.

It will be clear to those skilled in this art, and with the general objects of the present invention 65 in view, that changes may be made in the steps of the method and in the details of structure, the described and illustrated embodiments thereof being intended as exploitations of the underlying essentials of the invention, the features whereof are definitely stated in their true scope in the 70 claims herewith.

What is claimed as new, is:

1. A step product in the manufacture of calking 75 welts comprising a strip of material having an intact outer edge face, a portion of the grain face

adjacent its inner edge face removed to form a flange thinner than the strip, and a portion of its flesh face removed to form two internal convergent faces, one of which meets the flesh face and the other one of which meets the intact 5 outer edge face.

2. A step product in the manufacture of calking 10 welts comprising a strip of material having a grain face, a flesh face, an intact outer edge face, and a portion of its flesh face removed to form two internal convergent faces, one of which meets the flesh face and the other one of which meets the intact outer edge face.

3. A step product in the manufacture of calking 15 welts comprising a strip of material having an intact outer edge face, a portion of the grain face adjacent its inner edge face removed, and a portion of its flesh face removed to form two internal convergent faces, one of which meets the flesh face and the other one of which meets the 20 intact outer edge face, the gap in the flesh face having a width substantially commensurate with the thickness of the outer edge face.

4. In a welt shoe, the combination with an upper, 25 a welt, an insole, and an inseam for securing them together, of a calking welt, lying in the shoe crease formed between the upper and the welt and secured by the inseam, composed of a single strip of material presenting to view a grain face and having a concaved flesh face engaged 30 with the upper.

5. In a welt shoe, the combination with an upper, 35 a welt, an insole, and an inseam for securing them together, of a calking welt, lying in the shoe crease formed between the upper and the welt and secured by the inseam, composed of a single strip of material presenting to view a grain face and having a concaved flesh face engaged with the welt.

6. That improvement in the art of making 40 calking welts which consists in removing a triangular portion from the flesh face of a strip of welting adjacent one edge face leaving it intact, and bending the intact edge face approximately 45 90° to bring it into the plane of the flesh face from which the triangular portion had been removed.

7. That improvement in the art of making 50 calking welts which consists in removing a triangular portion from the grain and flesh face, respectively, of a strip of welting leaving one edge face intact and turning the intact edge face to close up the gap formed in the flesh face by the removal of the triangular portion.

8. That improvement in the art of making 55 calking welts which consists in removing a triangular portion from the grain and flesh face, respectively, of a strip of welting leaving one edge face intact, turning the intact edge face to close up the gap 60 formed in the flesh face by the removal of the triangular portion, and convexing the grain face.

9. That improvement in the art of making 65 calking welts which consists in removing a triangular portion from the grain and flesh face, respectively, of a strip of welting leaving one edge 70 face intact, molding the intact edge face and the grain face to close up the gap formed in the flesh face by the removal of the triangular portion and convex the grain face, and concaving the flesh faces.

10. A blank for use in the manufacture of calking 75 welts and the like which consists of a strip of leather having grain on one side and flesh on the other, a rabbet having two converging faces having been formed on the flesh side, the widest di- 75

mention of the rabbet between said faces being substantially commensurate with the thickest part of the strip.

- 5 11. A calking welt comprising a strip of material having an inner vertical flesh face, an outer convexed grain face, an integral concaved flesh face on one side extending from the upper end of the inner vertical flesh face to the convexed grain face, and a composite concaved flesh face on the 10 other side extending from the lower end of the inner vertical flesh face to the convexed grain face, one of the components of said composite face having a dimension substantially commensurate with the thickest part of the strip.
- 15 12. That improvement in the art of making one piece leather calk welting, and the like, which comprises removing a strip of grain leather from a strip of leather, having grain on one face and flesh on the other faces, adjacent one edge to 20 leave a flange thinner than the original strip, removing a triangular portion from the flesh face opposite the grain face leaving one edge face intact, and turning the intact edge face to close up the gap formed in the flesh face by the removal of the triangular portion.
- 25 13. A calking welt comprising a strip of material having an inner vertical flesh face, an outer

convexed grain face, an integral flesh face on one side extending from one end of the inner vertical flesh face to the convexed grain face, and a composite flesh face on the other side extending from the other end of the inner vertical flesh face to the convexed grain face, one of the components of said composite face having a dimension substantially commensurate with the thickest part of the strip.

- 5 14. That improvement in the art of making one piece leather calk welting, and the like, which comprises removing a strip of grain leather from a strip of leather, having grain on one face and flesh on the other faces, adjacent one edge to 10 leave a flange thinner than the original strip, removing a portion of the flesh adjacent the other edge to leave two grain covered portions of substantially the full thickness of the original strip, bending one of said thick grain covered portions 15 substantially 90° to bring a flesh edge face there- 20 of into the plane of the flesh face on the other one of said thick grain covered portions to form a composite flesh face and a bead having said grain on its outer face, and molding said bead to shape.

LLOYD F. PLUMMER.
